SULFIDE METHOD PLUTONIUM SEPARATION

Robert B. Duffield, Champaign, Ill., assignor to the United States of America as represented by the United States Atomic Energy Commission

No Drawing. Application May 4, 1948
Serial No. 25,075

6 Claims. (Cl. 23—14.5)

This invention is concerned with a method for separating plutonium from impurities normally associated therewith in neutron-irradiated uranium.

In this specification and claims the name of the element is used to designate the element generically either in its element state or combined in a compound unless otherwise indicated by the sense in which it is used, for example by a specific designation, such as "metal" or "elemental."

Natural uranium is composed of three isotopes—namely, U^{234} , U^{235} , and U^{238} , the latter being present in excess of 99% of the whole. When U^{238} is subjected to the action of slow or thermal neutrons a fourth isotope, U^{239} , is produced having a half-life of twenty-three minutes which undergoes beta decay to Np^{239} , which in turn decays further by beta radiation with a half-life of two and three-tenths days to yield plutonium. In addition to the formation of Pu^{239} there are simultaneously produced other elements of lower atomic weight known as fission fragments. These fission fragments are isotopes of elements having atomic numbers from between approximately 32–64. These isotopes as originally produced are considerably overmassed and undercharged and hence are highly unstable. By beta and gamma radiation, however, they quickly transform themselves into isotopes of these various elements having longer half-lives. The resulting materials are commonly known as fission products. The various radioactive fission products have half-lives ranging from a fraction of a second to thousands of years. Those having half-lives which are very short may be substantially eliminated by aging the material for a reasonable period before handling. Those with very long half-lives do not have sufficiently intense radiations to endanger personnel protected by moderate shielding. On the other hand, the fission products having half-lives ranging from a few days to a few years have dangerously intense radiations which cannot be eliminated by aging for practical storage periods. These products are chiefly radioactive isotopes of Te, I, Cs, Ba, La, Ce, Sr, Zr, Cb, and Rb.

It may be readily seen that plutonium, produced as generally set forth above, is contaminated with considerable quantities of uranium and fission products. In fact, the plutonium constitutes only a very minor portion of the irradiated mass, i. e., less than 1% thereof. In view of such a low concentration of plutonium in the irradiated metal it becomes apparent that the procedure employed to recover that element must be highly efficient in order to be at all practicable. In addition to the recovery of the plutonium, it is highly desirable to separate the fission products from the plutonium, since these have exceedingly important uses as therapeutic agents and are also used as radioactive tracers in chemical, medical, and industrial research.

It is an object of this invention to provide a method of separating plutonium from an aqueous solution in which the plutonium is contained in a small concentration.

2

An additional object of this invention is to provide a convenient and efficient method of recovering plutonium from impurities commonly associated therewith in neutron-irradiated uranium.

5 Broadly, the present invention involves the treatment of plutonium in a lower state of oxidation, with a soluble sulfide in the presence of a source of uranyl ions. The plutonium which is contained in an aqueous, alkaline solution, is contacted with a soluble sulfide compound, 10 whereby a precipitate is formed which contains a substantial part of the plutonium present. The precipitate is separated from the solution, thus effectively separating the plutonium from such impurities as are soluble in the solution under these conditions. The precipitate is then dissolved by treatment with an aqueous solution containing carbonate ion in excess of that stoichiometrically required to form a soluble carbonate complex with the uranium and the plutonium contained in the precipitate. This treatment brings the plutonium and uranium into 20 solution, but does not affect the fission product sulfides which are not soluble in an excess carbonate solution, for example, the ceric sub-group rare earth sulfides. The solution is then centrifuged, thus separating the plutonium from these insoluble fission product sulfides.

15 In its preferred embodiment, this process comprises the treatment of plutonium, contained in an aqueous alkaline solution, in a reduced state, i. e., the tri- or tetravalent state. This solution may be formed by dissolving neutron-irradiated uranium in nitric acid and then converting 20 the solution to the alkaline state by addition of an alkali hydroxide. The solution formed in this manner will contain the plutonium in very small concentration, uranyl ions and fission products. The plutonium-containing solution is then treated with a soluble sulfide, and preferably hydrogen sulfide, whereby an insoluble precipitate is 25 formed. This precipitate contains the uranium, plutonium, and those fission products present, which form insoluble sulfides in alkaline solution. The fission products, such as Sr, Te, Rb, and Cs, which form soluble sulfides in 30 alkaline solution, will remain in solution and by the separation of the insoluble plutonium-containing precipitate from the solution, the plutonium will be effectively freed from this type of fission products. Separation of the precipitate may be effected by any of the usual methods, 35 such as centrifugation, decantation, or filtration. Following the separation of the precipitate, it may be washed with water and then treated with a solution containing carbonate ion in excess. The plutonium in its lower oxidation states forms a very stable complex with carbonate ion and the carbonate solution thus will effectively dissolve the plutonium. Uranyl ion is dissolved in the same way and so is also brought into solution. Certain of the 40 fission products which form insoluble sulfides, notably cerium, lanthanum, and the other members of the ceric 45 sub-group of the rare earth, are insoluble in excess carbonate, so these will remain in the solid form as the sulfides, in the presence of the excess carbonate solution. These undissolved sulfides may be separated from the solution by centrifugation, filtration, or decantation. This 50 step will effectively separate the plutonium from the greater portion of the remaining contaminants. Plutonium may then be separated from the uranyl ion-containing solution by any of the usual methods, such as precipitation with a lanthanum fluoride or bismuth phosphate carrier. The process of this invention has been described as applied to the separation of plutonium contained in solution in such small concentration that it must be precipitated with an auxiliary precipitate. The process 55 may be equally advantageously employed where the plutonium is present in solution in such concentration that it may be directly precipitated. In case the plutonium is 60 65 70

present in such concentration the procedure for separating the plutonium is the same as that previously set forth, except that the precipitation of the plutonium may be carried out in a solution which does not contain uranyl ions.

The advantages of the process of this invention are readily apparent. It provides a simple method for separating plutonium from solutions in which the plutonium is contained in small concentrations. It also provides a novel method of separating plutonium from such contaminating elements, normally associated with plutonium in neutron-irradiated uranium, as form soluble sulfides in an aqueous alkaline solution. It further provides a method of separating plutonium from the contaminating elements, the sulfides of which are insoluble in an excess carbonate solution. The separation method is a simple one, which does not require the use of any highly corrosive reagents and efficiently separates plutonium from some of the most highly radioactive fission products.

Now that this invention has been broadly described, it may be further illustrated by the following specific examples.

Example I

A 0.5 M potassium hydroxide solution was prepared in a volume of about 5 cc. To this solution was added 0.5 mg. of potassium diuranate obtained from neutron-irradiated uranium, containing a tracer quantity of 50-year plutonium in the tetravalent state. Hydrogen sulfide was then passed into the solution for ten minutes. The uranyl precipitate thus formed was then separated from the solution by centrifugation. The precipitate and the supernatant solution were analyzed and it was found the plutonium had carried with the precipitate to the extent of 81% with 12% of the plutonium unaccounted for and the balance remaining in the supernatant solution.

Example II

A 0.5 mg. sample of the uranyl precipitate obtained in the manner described in the preceding example was introduced into 5 cc. of a 0.5 M potassium hydroxide solution. This solution was then made 0.5 M in K_2CO_3 and 0.6 M in NH_4OH . The precipitate was digested for about thirty minutes in this solution, which treatment effected the dissolution of the greater part of the precipitate. The balance of the undissolved precipitate was then separated from the solution by centrifugation and the precipitate and solution analyzed by radiometric methods. The solution was found to contain 91% of the plutonium contained in the original precipitate with 6% remaining in the undissolved precipitate and 3% unaccounted for.

It will be apparent to those skilled in the art that various modifications in the present invention exist. In general, it may be said that any process for the isolation of plutonium, wherein the plutonium is separated from an alkaline solution either directly or together with a uranyl sulfide carrier, is to be considered as lying within the scope of the present invention.

What is claimed is:

1. The process of separating plutonium from contaminants normally associated therewith in neutron-irradiated uranium, which comprises treating an aqueous alkaline solution containing plutonium values and contaminants normally associated therewith, said plutonium having a valence state less than +5, in the presence of a source of

uranyl ions, with a soluble sulfide, whereby a plutonium-containing uranyl precipitate is formed, separating said precipitate from the solution, treating said precipitate with an aqueous solution containing carbonate ion in excess, 5 whereby the plutonium is dissolved away from the fission product sulfides insoluble in excess carbonate, and separating said insoluble fission product sulfides from the plutonium-containing solution.

2. The process of claim 1 in which the soluble sulfide 10 is hydrogen sulfide.

3. The process of separating plutonium values from contaminants normally associated with plutonium in neutron-irradiated uranium, which comprises treating an aqueous alkaline solution containing said plutonium values in a valence state less than +5, fission product values and a source of uranyl ions with a soluble sulfide, whereby a uranyl precipitate containing said plutonium values and insoluble fission product values is formed, separating said precipitate from the solution which contains fission product sulfides which are soluble in alkaline solution, treating said precipitate with an aqueous solution containing hydroxide ions and carbonate ions in excess of the amount stoichiometrically required to form a soluble carbonate complex with the uranyl and plutonium ions in said precipitate whereby the plutonium is dissolved away from the fission product sulfides insoluble in excess carbonate, and separating said insoluble fission product sulfides from the solution containing said plutonium values and said uranium values dissolved therein.

4. The process of separating plutonium from contaminants normally associated with plutonium in neutron-irradiated uranium, which comprises treating said plutonium contained in an aqueous alkaline solution in the tetravalent state, with a soluble sulfide whereby a plutonium-containing precipitate is formed, separating said precipitate from the solution, treating said precipitate with an aqueous solution containing carbonate ion in excess, whereby the plutonium is dissolved away from the fission product sulfides insoluble in excess carbonate, and separating said insoluble fission product sulfides from the plutonium-containing solution.

5. The process of separating plutonium from an aqueous alkaline solution in which plutonium is contained in very dilute concentration, in a valence state less than +5, which comprises treating said plutonium with a soluble sulfide in the presence of a source of uranyl ions, whereby a plutonium-containing uranyl precipitate is formed, and separating said plutonium-containing uranyl precipitate from the solution.

6. The process of separating plutonium from a contaminant whose sulfide is soluble in an aqueous alkaline solution and which is normally associated with plutonium in neutron-irradiated uranium, which comprises treating said plutonium contained in an aqueous alkaline solution in a valence state less than +5, in the presence of a source of uranyl ions, with a soluble sulfide whereby a plutonium-containing uranyl precipitate is formed, and separating said precipitate from the solution which contains said contaminant.
